UNITED STATES PATENT OFFICE.

HARMON DE LEON MOÏSE, OF SUMTER, SOUTH CAROLINA.

GATE-LATCH.

1,044,684.

Specification of Letters Patent. Patented Nov. 19, 1912.

Application filed January 25, 1912. Serial No. 673,368.

To all whom it may concern:

Be it known that I, HARMON DE LEON MOÏSE, a citizen of the United States, residing at Sumter, in the county of Sumter and 5 State of South Carolina, have invented certain new and useful Improvements in Gate-Latches, of which the following is a specification, reference being had to the accompanying drawings.

10 This invention relates to locks, and more particularly to that class that are known as gate-latches.

The main object of this invention is to provide a latch which can be used for holding a gate in open and closed positions, and at the same time may be reinforced in its locking action by means of a padlock or other suitable fastening device.

15 Further objects are to arrange the latch so that it may be constructed easily and at a comparatively low cost, and so that it may be easily manipulated from either side of the gate on which it is placed.

Another object is to have the latch applicable for use with gates of all kinds, and under all conditions.

Other objects of this invention will become apparent as it is more fully set forth.

The device referred to in this specification 0 consists, in general, of a symmetrical member adapted to project on either side of a gate and serve as a catch for locking the gate in either open or closed positions, suitable means being provided for attaching said 5 member to a gate. The member is also arranged so that a padlock may be used for attaching it to a hasp, and at the same time not interfering in any way with the action of the latch, but on the other hand adding 10 several features which are advantageous to it.

In the accompanying drawings which illustrate by way of example, an embodiment of this invention, Figure 1 is a view 15 in perspective of a latch embodying this invention. Fig. 2 is a plan view showing the latch applied to a gate in closed position, and Fig. 3 is a detail showing the method of applying a padlock to the latch.

Similar reference characters refer to similar parts throughout the drawings.

In the construction shown 1 denotes a spring hinge of any suitable form, to which the latch member 2 is attached. The end portions 3 and 4 of the member 2, are bent 55 back on themselves in the manner clearly shown in the drawings, so as to provide triangular tongues, that will engage and catch on a staple 6, disposed in a stopping post 7, and at the same time permit a padlock 60 8 to be used for locking the staple and end or tongue caught on the same.

The manner of applying the padlock to the staple and end of the latch member is clearly indicated in Fig. 3. It is obvious 65 that by connecting the end 4 to another staple, suitably positioned, that the gate can be locked in open position also, in a similar manner to that just described.

It will be noted that the form of tongue 70 used in this device provides a comparatively strong catch, as well as providing a means for the easy manipulation of the lock. As the catch projects on both sides of the gate, indicated at 5, it may be actuated from 75 either side of the same.

The device while effective for the purpose for which it is intended is comparatively simple in its construction and may be manufactured at a very low cost. It is very easily 80 attached to a gate, and is without any parts that are loose or liable to become easily lost or detached.

Having thus described this invention what is claimed is:

In combination with a padlock and a bent wire hasp disposed so that its stems will be over one another, a latch for gates comprising a spring hinge, a latch member rigidly secured to one leaf of said hinge, said member having its end portions bent into right-angle triangle form, whereby said end portions will catch on said hasp and permit said padlock to lock the same to one of said end portions substantially as described. 95

In testimony whereof I hereunto affix my signature in the presence of two witnesses.

HARMON DE LEON MOÏSE.
